The ornamental design for a toothbrush with polishing member, as shown and described.

DESCRIPTION

FIG. 1 is a bottom perspective view of a toothbrush with polishing member showing our new design;

FIG. 2 is an enlarged side elevational view thereof, the opposite side being a mirror image;

FIG. 3 is a bottom plan view of FIG. 2;

FIG. 4 is a front elevational view of FIG. 2;

FIG. 5 is a rear elevational view of FIG. 2;

FIG. 6 is bottom perspective view of a second embodiment of the toothbrush with polishing member;

FIG. 7 is an enlarged side elevational view of FIG. 6, the opposite side being a mirror image;

FIG. 8 is a bottom plan view of FIG. 7;

FIG. 9 is a front elevational view of FIG. 7; and,

FIG. 10 is rear elevational view of FIG. 7.

The broken lines showing the upper portion of the head and a handle are included for the purposes of illustrating portions of the article that form no part of the claimed design.
